UNITED STATES PATENT OFFICE.

CHARLES T. SHREVE, OF DELAWARE, CAMDEN COUNTY, NEW JERSEY.

HOOD FOR VEHICLE-TOPS.

SPECIFICATION forming part of Letters Patent No. 300,520, dated June 17, 1884.

Application filed November 13, 1883. (No model.)

To all whom it may concern:

Be it known that I, CHARLES T. SHREVE, of Delaware township, in the county of Camden and State of New Jersey, have invented 5 a new and useful Improvement in Hoods for Vehicle-Tops, of which the following is a full, clear, and exact description.

Reference is to be had to the accompanying drawings, forming a part of this specification, in which similar letters of reference indicate corresponding parts in all the figures.

Figure 1 is a front elevation of my improvement shown as applied to the front bow 15 of a vehicle-top. Fig. 2 is a sectional side elevation of the same, taken through the line $x-x$, Fig. 1. Fig. 3 is a plan view of the hood extended. Fig. 4 is a plan view of the hood folded. Fig. 5 is a sectional elevation of the 20 hood folded, taken through the line $y-y$, Fig. 4.

The object of this invention is to secure better protection from rain and snow to persons riding in top carriages than is attainable from the ordinary carriage-tops.

25 The invention consists in a hood for vehicle-tops formed of a plate made in two parts, connected at their adjacent edges by hinges, so that the said hood can be readily folded for convenient transportation. In the hood, near 30 its inner edge, are formed short slots, to receive the eyes of eye-screws screwed into the front bow of the carriage-top, so that the said hood can be readily applied and removed, as will be hereinafter fully described.

35 A represents the front bow, and B the cover, of an ordinary vehicle-top, which may be fixed or folding, as the character of the vehicle may require.

C represents the hood, which may be made 40 of straw-board, book-binders' board, leather, wood, metal, or other material that has the necessary flexibility, so that it will bend to fit the curved corners of carriage-tops, and that has the necessary stiffness to maintain itself

in shape when bent without the assistance of 45 bows. The hood C is made in two equal parts, which are connected at their adjacent ends by hinges D, as shown in the drawings, so that the said hood, when not required for use, can be folded and laid upon the seat beneath the 50 cushion, so as to be wholly out of the way and out of sight. In the end and middle parts of the hood C, near its inner edge, are formed short slots E, to receive the eyes of eye-screws F, screwed into the front bow, A, so that when 55 the said eyes are in line with the slots E the hood C can be readily applied and removed, and can be secured in place by turning the eye-screws F one-quarter around, so as to bring their eyes across the slots E, as shown 60 in Fig. 2.

The hood C can be covered with leather, rubber cloth, or oil-cloth, to correspond with the cover B.

I am aware that a vehicle-hood has been 65 provided with a single hinge at one edge, upon which it may be folded by wrinkling the body of the hood into deep plaits or folds, and that wagon-top bows have been provided with hinges; but neither of these would be suitable 70 for my stiff-plate hood, and I do not claim them as my invention.

Having thus described my invention, I claim 75 as new and desire to secure by Letters Patent—

The combination, with two plates having the characteristics of flexibility and stiffness, as described, of hinges joining them, and means for securing them to a carriage-top, substantially as and for the purpose specified, whereby 80 the said plates may be folded flat together when not in use, and may be sprung to fit the curves of a carriage-top, as described.

CHARLES T. SHREVE.
